NEW YORK.

METHOD OF AND APPARATUS FOR TREATING HYDROCARBON OILS.

1,283,202.

Specification of Letters Patent. Patented Oct. 29, 1918.

Application filed January 17, 1917. Serial No. 142,833.

To all whom it may concern:

Be it known that we, ERNEST A. JOHNSON and WILLIAM SNODGRASS, citizens of the United States, and residents of Woodhaven and Brooklyn, in the counties of Queens and Kings, respectively, and State of New York, have invented certain new and useful Improvements in Methods of and Apparatus for Treating Hydrocarbon Oils, of which the following is a specification.

The present invention relates to a method of and apparatus for treating volatile hydrocarbon compounds from petroleum residues or pitches which are ordinarily non-volatile, and consists in the arrangement of steps of procedure, and combinations and arrangements of elements of apparatus, hereinafter described and particularly set forth in the accompanying claims.

The invention has for its purpose to devise a method of treating hydrocarbons in a manner to obtain the maximum yield of its most valuable and marketable product and wherein the process is a simple one and easily performed.

The further purpose of the invention is to construct an apparatus in which the maximum thermal efficiency of the fuel is utilized to recover in a rapid and economical manner the volatile constituents of the oil; and wherein the stills are constructed and arranged in a manner to present the maximum heating surface for vaporization.

The further purpose of the invention is to provide a condensing system in which the vapor products are initially subjected to atmospheric influences to be partially condensed while under pressure, then permitted to expand for further condensing and finally treated in a liquid-cooled condenser to be finally condensed and thence collected.

The invention further has for another purpose to construct a novel type of still unit that is adapted to be used in any system for the treatment of hydrocarbon now installed, and the atmospheric condenser is constructed to the same end.

The apparatus is disclosed by way of illustration in the accompanying drawings, wherein:

Figure 1 is a view partly in section and partly in side elevation of a portion of the apparatus;

Fig. 2, a similar view of the remaining portion thereof;

Fig. 3, a view partly in section and partly in elevation of the apparatus taken on the line 3—3 of Fig. 1;

Fig. 4, a cross-sectional view partly in elevation taken on the line 4—4 of Fig. 3;

Fig. 5, an enlarged detail view, partly in section of one of the still units;

Fig. 6, a top plan view thereof;

Fig. 7, a cross-sectional view of one of the tubes of the still unit, and Fig. 8, a detail view of a portion of the condenser system.

Heretofore, in the manufacture of gasoline from petroleum residues or pitches by pressure distillation, it has been the practice, through the type of apparatus in use, to distil from the "batch". This method involves a considerable loss of time due to the fact that the large volume of oil contained in the reservoirs or stills has to be heated before the volatile constituents of the oil are vaporized and released for condensation.

By the use of the type of apparatus herein employed, a great saving in both time and fuel is effected, due to the fact that reservoirs are used as preheaters or auxiliary stills and are arranged for distributing a large volume of oil over a maximum area through a plurality of still units which form the main still of the apparatus.

Furthermore, by providing a maximum heating surface and utilizing the flames or heated gases to heat both the main and auxiliary stills, it is obvious that the loss of heat is reduced to a minimum, and that by properly regulating the several valves of the system it is possible to accurately control the boiling point of the distillate and thus counteract the effect of uneven firing under the several stills.

Referring to the construction in further detail, the system embodies essentially a furnace structure, a main still, auxiliary stills, vapor reservoirs and a deposit receptacle, and atmospheric condensers and a water-cooled condenser, together with their respective auxiliary elements, and in this order the construction will be now described in detail.

The furnace comprises an ordinary masonry structure 1, providing a main combust-

tion chamber 2, and a pair of auxiliary combustion chambers 3 disposed to either side of and above said main chamber as shown in Fig. 3. The auxiliary chambers 3 are connected to communicate with the main chamber 2 through the combustion passage-ways 4 to the end that the products of combustion formed in the main chamber may be utilized in the auxiliary chambers before passing off through the outlet flue 5 to the chimney-flue 6, as shown in Fig. 4.

A main still comprising a plurality of independent still units is located in the main chamber 2 (see Fig. 1), directly in the path 15 of the flame or heated gases and are disposed for substantially the full length of the fire-place. Each of the said units (see Fig. 5) consists of a pair of drums 7 and 8 arranged in axial alinement and connected 20 to communicate by the several tubes 9 secured thereto in any approved manner, and the lower drum 8 of each unit has a pair of pipe connections 10 for coupling to the several pipe lengths or branches 11 that respectively communicate with the manifolds 12 located in the chambers 13 formed in the furnace wall.

The upper series of drums are wholly enclosed within a casing 9^a constructed of fire tiles or other suitable material to protect 30 said drums and the tube joints from deterioration due to the intensity of the flame, and said casing forms a baffle wall that assists in directing the flame and heated gases 35 into the fire tubes of the several units.

A plurality of open-ended fire tubes 14 is mounted in each drum and passed therethrough and through the tubes as shown in Figs. 5, 6 and 7, and the upper ends of said 40 tubes are flared or funnel-shaped as at 15, to better admit the flame or heated gases that pass through and about the tubes, uniformly throughout their length and along substantially the lines indicated by the arrows in Figs. 1 and 3. Each drum is constructed with a manhole opening closed by the plates 16, giving access to the interior of the drums and pipe ends for fitting, repairing or for cleaning.

By constructing the still units of a pair of upper and lower drums connected to communicate by a plurality of concentric tubes, it is obvious that when the space between the tubes is filled with oil a plurality of hollow 55 columns of oil are formed and presented to be heated by the direct action of the flame or heated gases.

The several units of the still constitute the main distiller of the system, and are located to be heated by the fuel at its maximum intensity. The products of combustion of lesser intensity are utilized to vaporize the hydrocarbon in the auxiliary stills, as heretofore stated.

The auxiliary stills consist of the pair of

horizontal cylinders 17, suitably mounted on the several supported members 18 on the furnace structure above the combustion chambers 3, and said cylinders or reservoirs have communication with the two manifolds 70 12 through the downwardly disposed pipes 19 located preferably at the rear end of the furnace to give easy access to the controlling valve 20 (see Fig. 4) and by which the flow of oil from the reservoir 17 to the still units 75 may be regulated.

The combustion products entering the chambers 3 are controlled by the pair of dampers, valves or gates 21 (see Fig. 3) that serve to admit such products into said 80 chambers, or to divert the same to pass through the flue 22, leading to the stack-flue 6 (see Fig. 4). An auxiliary means is provided for producing combustion of fuel in the two chambers 3 and consists of a 85 plurality of pipes 23 provided with apertures or burners of suitable type and which communicate with the supply pipes 24 and 25, leading to the source of oil or gas and air under pressure respectively. 90

The generated vapors from the units of the main still are collected in a vapor reservoir 26 (Figs. 1 and 3), mounted on a superstructure 27 supported by the furnace walls and communicating with the several 95 drums 7 of the units by the vertically disposed pipe connections 28 and 29 that are respectively connected by the elbow or swing joints 30 to allow for expansion and contraction, as will be understood. A deposit 100 drum 31 is located below the several drums 8 of the units (see Figs. 1 and 3), and communicates therewith through the pipe connections 32, and such deposit as collects therein is adapted to be carried off through 105 the pipe 33 by the pump 34, and a cooling coil 35 in the tank 36 connects with said pipe 33 and with the pipes 37 (one being shown) leading to the bottom of the auxiliary stills 17 for a like purpose. The 110 pipe 33 is suitably provided with controlling valves 38 and 39, and the pipe 37 is likewise provided with valves 40 and 41. The position of the several valves (38, 39, 40, 41) allows of collecting the sediment in either 115 or both the main and auxiliary stills as desired.

The vapors from the reservoir 26 collect in the drum 42, from which a dephlegmator or runback, 43 inclines upwardly for carrying the vapors therefrom to the condenser (see Figs. 1 and 2), and in like manner dephlegmators (not shown) convey the vapors collected in the drums 44 on the auxiliary stills 17 to the distilling apparatus. 125 The drum 42 is provided with a safety valve 45 to relieve excessive pressure in the drum and the drums of the auxiliary stills would be in like manner equipped.

The condensing apparatus consists of an 130

atmospheric condenser or radiator, and expansion tank, and a water-cooled condenser that are connected to communicate with the dephlegmator 43 through the pipes 46 and 47, in the manner shown. The highly volatile oil vapors will pass from the dephlegmator into the atmospheric condenser through the pipe 46, and the passage of such vapors are adapted to be manually controlled by the hand-operated valve 48. The pipe 47 is provided as an emergency relief, and through the hand operated valves 49 and 50 the emergency relief is controlled when occasion demands.

15 A pressure gage 51, which indicates the vapor pressure, is mounted on the dephlegmator in close proximity to the atmospheric condensers, as shown in Fig. 2, and a temperature gage (not shown) for indicating 20 the temperature in the still is also employed.

20 The atmospheric condenser or still (see Figs. 2 and 8) consists of a pair of drums or manifolds 52 and 53 in superposed relation and connected to communicate by a plurality of relatively thin and exposed tubes 54 that are readily maintained constant with the temperature of the atmosphere. A third drum or manifold 55, disposed adjacent the drum 52, is connected to communicate 25 with the upper drum 53 by the series of bent tubes 56 similar to the tubes 54.

30 The partially condensed vapors pass from the atmospheric condenser into an expansion tank 57 that communicates with the drum 55 through the manifold piping 58, having controlling valves 59 and 61 which are utilized to control and maintain the desired pressure in the stills, dephlegmator and atmospheric condenser. Pipe connections 62 and 63 connect the tank 57 to communicate 35 with the atmospheric condensers associated with the two auxiliary stills. The tank 57 allows the partially condensed vapors to expand and be further condensed before 40 entering the coil 64 of the liquid-cooled condenser 65 to be finally condensed. The coil of the liquid-cooled condenser is of any suitable construction and communicates with the expansion tank 57 through the pipe 66 45 and directly with the dephlegmator 43 through the emergency relief pipe 47, as above indicated.

50 The finally condensed vapors are collected in the receiving tank 68 through the pipe 69 having a suitable gas-check 70 which relieves the gas pressure which is liable to accumulate in the coil 64 and obstruct the action of the apparatus, and said receiving tank is fitted with an outlet pipe 71 leading to an 55 accumulator, and a test tap 72 is also provided to test the products of condensation when desired.

55 In operation, the stills are filled through suitable manhole openings 73 on the auxiliary stills from the pipe 74, leading to the

60 pipe line or other source of supply, and the several units of the main still are filled with oil through the manifolds 12 and feed pipes 19. The condensing system is closed until the proper temperature and pressure have 65 been reached in the main and auxiliary stills, and due to the greatly increased surface presented to the flames or heated gases, it will be evident that the oil will begin to volatilize in a relatively short period and that the 70 lighter constituents will begin to be liberated.

75 When the predetermined temperature and pressure have been reached, the controlling valve 48 is opened so that the vapors enter 80 and traverse the cooling tubes of the radiator and transferring their heat to the walls thereof, a portion of the higher boiling point fractions being thereby condensed and caused to drain downwardly into the dephlegmator 85 and returned to the still to be again treated. The desired portions, however, pass through the radiator in the form of a cooled and partially condensed vapor and by manipulating the control valves 59 and 61 the vapors 90 are permitted to flow to the expansion tank 57 where the temperature and pressure are reduced, thus increasing the condensation effect upon vapors therein. From the expansion tank the vapors pass into the water-cooled condenser where they are finally 95 treated and then collected.

100 It is obvious that those skilled in the art may vary the details of construction and arrangement of parts without departing from the spirit of our invention, and therefore we do not wish to be limited to such features except as may be required by the claims.

105 What we claim as new and desire to secure by Letters Patent of the United States is:

1. The process of treating petroleum hydrocarbons, which consists in producing an upwardly-flowing hollow column of oil of substantially constant cross-section, then 110 subjecting the interior and exterior of the column substantially uniformly throughout its length to a current of heat to obtain a high temperature and pressure to produce mixed vapors, leading the vapors of distillation from the column to an atmospheric condenser to be partially condensed by radiation, releasing the partially condensed vapors to expand, finally condensing the 115 products by liquid cooling and collecting the 120 products of condensation.

2. The process of treating petroleum hydrocarbons, which consists in supplying hollow columns of oil from a source of bulk supply, then producing a flow-path for a 125 heating medium leading successively into heating relation with the exterior and interior of the columns and the bulk supply source, whereby the oil delivered to the columns will be preheated, maintaining both 130

- the bulk supply and hollow columns under vapor pressure to produce mixed vapors, leading the vapors of distillation from the columns and bulk supply to a condenser and 5 collecting the products of condensation.
3. The process of treating petroleum hydrocarbons, which consists in providing a bulk supply forming an auxiliary heating station, feeding the material from the bulk 10 supply to the main heating station in the form of a plurality of sets of hollow columns of oil, heating said columns at said main station by passing a heating medium around the exterior and then through the interior of 15 the columns and then directing the heating medium to the auxiliary station to heat the bulk supply, and maintaining both the hollow columns and bulk supply under vapor pressure to produce mixed vapors.
- 20 4. In the process of treating petroleum hydrocarbons to produce condensation products, the method of producing vaporization of the oil which consists in distributing the oil into a plurality of upwardly-flowing hollow columns, subjecting the exterior and interior of each column to the action of heat currents to produce temperature and pressure conditions for the production of mixed 25 gases therein, collecting the vapors from the several columns, and condensing the vapors.
5. In apparatus for treating hydrocarbons and in combination, a plurality of still units each formed to distribute the oil in upwardly-flowing hollow column formation, 30 means for producing vaporizing action within a column by subjecting its opposite walls to heating temperatures, a vapor reservoir communicating with said units through restricted passageways, a dephlegmator inclining upwardly from the reservoir for carrying vapors therefrom, and a condenser in communication with the dephlegmator.
6. In apparatus for treating hydrocarbons and in combination, a plurality of still units 35 each formed to distribute the oil in upwardly-flowing hollow column formation, means for producing vaporizing action within a column by subjecting its opposite walls to heating temperatures, a vapor reservoir 40 communicating with said units through restricted passageways, a dephlegmator inclining upwardly from the reservoir for carrying vapors therefrom, an atmospheric condenser communicating with the dephlegmator, and a liquid-cooled condenser in controllable 45 communication with the dephlegmator and the atmospheric condenser.
7. In apparatus for treating hydrocarbons, 50 a still unit adapted to distribute the oil into hollow column formation while undergoing vaporization and comprising a pair of drums connected by tubes, open-ended tubes passing through the respective tubes and said 55 drums and adapted to form passageways for products of combustion, in combination with a vapor reservoir, and a condenser connected to and adapted to communicate with the reservoir, said drums being arranged in vertical axial alignment, said reservoir being positioned above and operatively connected with the upper drum by a restricted passageway.
8. In apparatus for treating hydrocarbons, 60 a still comprising a plurality of still units each adapted to distribute the oil into hollow column formation while undergoing vaporization and each consisting of a pair of drums, tubes connecting the drums, said tubes being externally exposed in the flow path of products of combustion, and open-ended tubes passing through the respective tubes and drums and forming internal passageways for the products of combustion, in combination with a vapor reservoir common to and communicating with the several still units, and a condenser connected to communicate with the reservoir, said units being arranged in parallel arrangement with the drums in vertical axial alignment, said reservoir being positioned above and operatively connected with the uppermost drums of the several units through restrictive passageways.
9. In apparatus for treating hydrocarbons, 65 a plurality of substantially non-communicating still units each adapted to distribute the oil into hollow column formation while undergoing vaporization, a vapor reservoir common to and communicating with said units, said reservoir being positioned above the units and communicating therewith through restricted passageways, a condenser connected to communicate with the reservoir, and a deposit drum located below and in common communication with the several units.
10. In apparatus for treating hydrocarbons, a furnace structure, a plurality of parallel still units located in the combustion chamber of the furnace structure and successively in the direction of flow of the fuel gases, said units each being formed to provide oil distribution in the form of hollow and continuous columns of oil while passing through said chamber, in combination with a vapor reservoir having restricted communication with the several still units, and a condenser communicating with the reservoir.
11. In apparatus for treating hydrocarbons, 75 a furnace structure having a combustion chamber and a channel spaced above and in communication with said chamber, a plurality of still units extending vertically through and exposed to the products of combustion of said chamber and open to said channel to provide a plurality of internal passageways for the products of combustion.

through each unit, said chamber and channel both in open communication with the source of products supply, each unit having means to distribute the oil in the form of hollow columns during vaporization and while passing through the chamber and including a pair of axially aligned drums, a casing separating said channel and combustion chamber and adapted to segregate the uppermost drums of the units from the chamber, and means common to the several units for suc-

cessively collecting and condensing the vapors produced by the stills.

Signed at borough of Brooklyn, in the county of Kings and State of New York, this 15 11th day of January, A. D. 1917.
